UNITED STATES PATENT OFFICE.

WILLIAM GREENWADE, OF ASH GROVE, MISSOURI.

CAR-COUPING.

SPECIFICATION forming part of Letters Patent No. 438,151, dated October 14, 1890.

Application filed June 14, 1890. Serial No. 355,508. (No model.)

To all whom it may concern:

Be it known that I, WILLIAM GREENWADE, a citizen of the United States, residing at Ash Grove, in the county of Greene and State of Missouri, have invented a new and useful 5 Car-Coupling, of which the following is a specification.

My invention is an improvement in car-couplings, and has for its object to provide a 10 coupling which will have a pin-support so constructed that it will not readily get disordered, which will be simple and cheap of construction.

With these objects in view the invention 15 resides in the various novel details of construction, and in the combination of parts, hereinafter fully described, illustrated in the drawings, and particularly pointed out in the claims.

20 In the drawings illustrating my invention, forming part of this specification, throughout which like letters of reference indicate corresponding parts, Figure 1 is a view in perspective of my car-coupling. Fig. 2 is a vertical longitudinal section of the draw-head. Fig. 25 3 is a detail view of one of the parts; and Fig. 4 is a side elevation of the draw-head, the pin-support having been removed.

In the drawings, A designates a draw-head 30 provided with the usual flaring mouth a, the pin-openings a' and a² above and below, through which the pin B is placed.

A' designates the recess in the draw-head, into which the flaring mouth a opens. This 35 recess A', when the parts yet to be described have not been placed therein, is of an L shape, the longer arm a³ of the L being horizontal, and the shorter arm a⁴ depending vertically therefrom, the draw-head A at the bend of 40 the L forming a shoulder a⁵, against which the link strikes when it enters the recess. The arm a³ of this L-shaped recess A' is extended laterally on one side through the draw-head, forming a slot a⁶ therein. The edges 45 of this slot are cut away squarely to form ways a⁷, in which works a slide to be hereinafter described. The rear end of the slot a⁶ is provided with a shoe a⁸, which receives the end of the slide and limits its movement 50 therein. The slot a⁶ ends behind the mouth of the draw-head; but the ways a⁷ are continued forward to the face of the draw-head,

wherein a shoulder a⁹ is provided. a¹⁰ is a bolt-opening in the draw-head on its upper side extending downward to the recess A'. 55

C is a pin-support having a longitudinal opening c, and being provided with the slide c', adapted to fit the ways a⁷. This slide c' has an enlarged end c², adapted to abut against the shoulder a⁹. It also has a handle c³. This 60 pin-support C is adapted to fit within the slot a⁶ and rest in the horizontal longer arm a³ of the recess A', and is retained in position therein by means of the bolt D, which passes through the bolt-hole a¹⁰ in the draw-head 65 and engages the pin-support C by passing through the longitudinal opening c. The pin-support is longitudinally adjustable, and when its forward end is below the pin-opening a' the end c² of the slide c' projects beyond the face of the draw-head. 70

From the foregoing description it will be evident that in order to set my improved coupling all that is necessary is to raise the pin B. Then by means of the handle c³ push 75 the pin-support C forward until its front end will support the pin B. The end c² will now project beyond the face of the draw-head A. When another draw-head carrying a link approaches my improved coupling thus set, the 80 link will pass beneath the pin B until it strikes the shoulder a⁵. Shortly before the link strikes the shoulder a⁵ the face of the approaching draw-head will strike the projecting end c² and drive the pin-support C 85 back until the faces of the draw-heads meet. The slide is stopped by the shoulder a⁹ and the shoe a⁸. During this operation the pin drops by its own weight and the act of coupling is complete. 90

At present I prefer in practice to make the pin-support C fit the horizontal longer arm a³ of the recess A' rather snugly, or else to coat the sides of the two with a gummy substance, in order that slight jars may not throw 95 the pin-support out of place.

Having thus described my invention, what I claim as new, and desire to secure by Letters Patent, is—

1. In a car-coupling, the combination of a 100 longitudinally-sliding horizontal pin-support with a slide adapted to move in ways upon the side of the draw-head and having an enlarged end, which when the support is set

projects beyond the face of the draw-head, as and for the purpose set forth.

2. In a car-coupling, the combination of a longitudinally-sliding horizontal pin-support with a slide adapted to move in ways upon the side of the draw-head and having an enlarged end adapted to rest in a shoulder at the forward part of the ways, the other end of the slide being adapted to fit within a shoe, substantially as and for the purpose described.

In testimony that I claim the foregoing as my own I have hereto affixed my signature in presence of two witnesses.

WILLIAM ^{his} X GREENWADE.
